UNITED STATES PATENT OFFICE.

CASSIUS C. PECK, OF WARSAW, NEW YORK.

STEAM-BOILER.

SPECIFICATION forming part of Letters Patent No. 498,941, dated June 6, 1893.

Application filed February 29, 1892. Serial No. 423,255. (No model.)

To all whom it may concern:

Be it known that I, CASSIUS C. PECK, a citizen of the United States, residing at Warsaw, in the county of Wyoming and State of New York, have invented certain new and useful Improvements in Steam-Boilers, of which the following is a specification sufficient to enable others skilled in the art to which the invention appertains to make and use the same.

My invention relates especially to the class of steam boilers known as shell boilers, and is applicable to the three divisions or types thereof known as stationary, marine, and locomotive boilers.

The main object of my invention is to increase the efficiency of shell boilers, to render them more safe in use than heretofore, and to insure the production of dry steam. This I accomplish by, and my invention consists in, the special combination and arrangement as herein set forth of a tubular shell boiler or heater and a steam separating drum, the two being connected and communicating with each other at two points below the water line, one connecting passage entering the lower portion of the heater shell for the return of the water thereto, and the other connecting passage opening into the heater shell a comparatively short distance below the said water line. By this means I attain a continuous, even, uniform, natural circulation of the whole body of water between and through the heater shell and the steam separating drum, entirely below a common water level, with the least possible disturbance of the said water surface. The effects of this uniform movement of the boiler water continuously in one direction may be summarized as follows: In firing up, the boiler water circulation commences as soon as fire is lighted in the furnace, the whole mass of water partaking of the gyratory motion imparted by the furnace heat according to the well known principle of water circulation. Thus, as the water in the heater becomes warm it rises in the heater and passes through the upper connection into the steam separating drum, below the water level and a corresponding amount returns to the boiler from the separating drum by means of the lower connection. This causes the whole structure to become uniformly heated, and preserves it from the immense strains due

to unequal expansion, which strains prove very injurious in practice, and oftentimes destructive in shell boilers of large size and of the usual construction. This objectionable feature of shell boilers as heretofore constructed is so well known that means are often employed for effecting a mechanical circulation of the water to insure uniform heating when starting a fire in the boiler furnace. The steady and rapid circulation of all the boiler water which I effect below the water level prevents settling of cold feed water in any part of the structure, and also tends to bring all solid deposits from the water to points where they can be blown out, or removed by hand. In its effects upon steam production the constant movement of the whole mass of water thus effected by me through the shell of the heater and the separator below a common water level common to both, is of especial importance. In passing over the heated surfaces of the fire tubes the water wipes off or absorbs heat rapidly, and at the same time removes steam bubbles as fast as formed, and conveys them in the most direct way to the point of delivery from the comparatively quiet surface of the water in the steam separating drum. In ordinary multi-tubular boilers there is necessarily great confusion of currents which reduces the efficiency or value of the heating surface and results in the generation of wet steam. The rising currents of steam and more highly heated water are met and opposed by corresponding currents of descending cooler water, thus interfering with the escape of steam bubbles and increasing the tendency to foam, while lessening the amount of heat which can be carried away from the tube surfaces. By my arrangement of the connections and circulation entirely below the water line I maintain an extended area of comparatively smooth undisturbed surface in the separator from which the steam readily escapes in a practically dry state. This is a result of unusual practical importance, and one not heretofore attained for the reason that the agitation incident to the various prior forms of circulation has invariably resulted in the production of wet steam.

I am aware that steam boiler shells have been constructed with steam drums or cylinders above said shells, and connected thereto

at two, or more points by means of short pipes extending from the upper part of the cylindrical boiler shell to the under side of said cylinder or drum above, but such structures 5 are not the equivalent of my invention. In such cases the connections are all practically on the same level and do not materially affect the circulation of water; whereas in my invention the essential feature is the creation 10 and maintenance of a natural but nevertheless positive circulation of the whole body of water below the water level between and through the boiler shell and steam separating chamber by conducting the more highly heated water from the top of the boiler shell to the steam separating chamber, below the water level and returning the cooler water from the said steam separating chamber to the lower portion of the boiler shell. Unless 15 the lower portion of the steam separating chamber is thus connected with the lower portion of the steam boiler shell below the water line the essential conditions of my invention are lacking and there can be no positive, uniform circulation of the whole body 20 of water in one direction below the liquid level common to both boiler and separator.

In the accompanying drawings, Figure 1, is a front view of my improved construction of 25 steam boiler; Fig. 2, a side elevation of the same, the furnace and supporting masonry being shown in vertical section on plane of line x, x , Fig. 1; Fig. 3, a rear elevation of the same. Fig. 4, is a central longitudinal vertical section also on plane of line x, x , Fig. 35 1. Fig. 5, is a transverse vertical section on plane of line y, y , Fig. 2, showing the connection between the upper part of the boiler shell and the steam separating drum; Fig. 6, 40 a transverse section on plane of line z, z , Fig. 2, showing a connection between the steam separating chamber and the lower portion of the boiler shell. Fig. 7, is a transverse sectional elevation showing the steam separating 45 chamber arranged vertically with relation to the horizontal boiler shell. Fig. 8, is a sectional elevation illustrating modifications in the relative arrangement of the boiler shell and steam separating chamber.

50 In so far as the main feature of my invention is concerned,—the maintenance of a circulation of the boiler water through the boiler and steam separator below the common water line, it is immaterial whether the boiler shell, A, is placed horizontally, vertically or at any intervening angle. In like manner the steam separating chamber B, may be placed horizontally, vertically or at any intervening angle; and its position with relation to the boiler shell A, may be varied. Thus in the first six figures of the drawings, both boiler shell and separating chamber are shown as arranged horizontally and parallel to each other, one above the other; in Fig. 7, 55 they occupy positions relatively at right angles to each other; while in Fig. 8, the boiler shell is arranged vertically, and the separat-

ing chamber is represented first, in vertical position in solid lines, and second, in horizontal position by dotted lines B'. In all of 70 these arrangements the connections between the boiler shell A, and the steam separating chamber B, are essentially the same,—the upper connection a , uniting the upper portion of the boiler shell with the steam separating 75 chamber B, below the water level w , and the lower connection b , uniting the said steam separating chamber B, below the water line w , with the lower portion of the boiler shell. Thus in either case the principle of operation 80 remains the same, the heated boiler water and steam being delivered from the upper end or side of the heater shell into an independent evaporating and circulating cylinder, from which the boiler water returns to the lower 85 portion of the heater shell, with the result of maintaining a continuous current of the whole body of boiler water below the water line in one direction through both shells. A preferred arrangement however is that illustrated 90 in the first six figures of the drawings, in which the boiler and evaporating chamber are arranged horizontally, the upper or short connection a , being made between the top of the boiler shell and the under side of the 95 evaporating chamber near the front or furnace end of the apparatus; and the lower or long connection b , between the under side of the steam separating chamber B, and the lower portion of the boiler shell A, consisting of an 100 annular passage or jacket surrounding the boiler shell and opening into the bottom of the boiler through an aperture a' , shown in Fig. 6. Instead of thus constructing the lower connection b , in the form of an annular 105 jacket, a pipe of circular cross section may be used, or two pipes, one on either side of the heater A, can be used to connect the latter with the separating drum B. The whole area of the shell A, (except the space for man 110 holes not shown) is occupied by longitudinal tubes or flues c , arranged at suitable distances apart with relation to each other, the intervening space being filled by the boiler water 115 which extends up to the level w , in the steam separating chamber B.

It will be noticed that by the arrangement illustrated in Figs. 1 to 6, the circulation of the boiler water will be effected below the water line in a direction opposite to that taken 120 by the products of combustion through the fire flues, thus rendering the transfer of heat from the furnace gases to the boiler water more effective and at the same time augmenting the circulation of the water since it attains to the highest degree of heat at the furnace end of the shell immediately under the short ejection passage a , leading from the top of the boiler shell to the steam separating chamber.

130 The front end of the boiler shell A, is set in and inclosed by the fire brick composing one wall of the furnace F, so that only the end plate or head and tubes are exposed to

the direct action of the furnace gases. This will be seen by reference to Figs. 2, 3 and 5, the latter showing a section of the solid wall of fire brick or other refractory material in which the end of the boiler shell is set.

5 The whole furnace is made of fire brick or other refractory material, the walls being of a thickness sufficient to prevent the escape of heat in any considerable degree. The upper front part *f*, of the furnace, is inclined toward the exposed head or end of the boiler shell cylinder so as to more effectually deflect and radiate the gases and heat into the fire flues.

15 The rear end of the boiler shell is formed with an extension *H*, beyond the rear end plate or head *a*, in which the fire tubes *c*, end. This extension *H*, is inclosed by an end plate *h*, and thus constitutes a smoke box into and 20 from which the products of combustion are drawn by means of a rotating fan *I*, the suction passage of which *i*, opens directly into and forms a continuation of the smoke box *H*.

I am aware that a boiler and an independent steam separating chamber have been arranged one above the other and connected by pipes for the purpose of effecting a circulation of the water between them, as in German Patent No. 2,400, of 1877; but in such case 25 the inlet into the independent steam separating chamber is above the water level therein whereas the essential and distinguishing feature of my invention, and the one to which I restrict myself, consists in arranging both 30 the inlet and outlet passages so that they open into the independent steam separating chamber below the water level therein. Where the inlet is situated above the water level as in the patent referred to the water has to be raised 35 bodily above the said water line, and this can only be done by the use of a comparatively small pipe or passage so as to compel the steam formed in the boiler to carry upward with it a certain amount of water, as happens 40 in the objectionable feature of "priming" to which this operation would be equivalent. If the upward passage to the independent separating chamber were made large enough the steam would bubble up freely through the 45 water without carrying any appreciable quantity of the latter over and the water would stand permanently in the connection pipe at the same level as that in the separating chamber, which water level being below the mouth 50 of the inlet would effectually prevent any material circulation of the water between the boiler and the separating chamber. Again if the connection or inlet pipe to the separating 55 chamber is made small enough to compel the steam to "prime" or carry over the water into the steam separating chamber, it not only impedes rapid circulation of the water but also 60 inevitably produces wet steam, one of the very results sought to be avoided by applicant.

I am also aware that water coils have been arranged in a furnace and connected with an

exterior steam separating chamber by a return conduit below the water line and a steam and hot water conduit opening into the said 7c separator chamber at or above the water line, as in the patent to Brock, No. 121,079, of November 21, 1871, but such an arrangement is not the equivalent of mine, which is designed especially for the production of dry 75 steam, whereas in the use of the coil referred to it would be practically impossible to obtain anything but wet steam. For instance, the water level in one form of the Brock apparatus is below the inlet while in the other 80 form it barely reaches above the lower edge of the small circular inlet, so that while natural circulation below the boiling point would be impossible in one form it would be so slow and slight in the other form as to be of no 85 practical utility; and even whatever slight circulation might be possible, below the boiling point, over the lower edge of the inlet port would be at the maximum only when the water approximated very nearly to the boiling 90 point, and could not remain long undisturbed for the reason that at the moment steam began to form in the coil it would displace the water, and the discharge into the separator would be an agitated mixture of steam 95 and water, which it is the express object of my invention to obviate. In fact by my invention I overcome the defects of all prior 100 circulatory systems and am enabled to evolve perfectly dry steam from a comparatively smooth liquid surface under which the circulation is maintained constantly and uniformly, the steam having ample opportunity in which to rise to the surface from the circulating water without agitating or disturbing the latter. 105

The smoke box extension and the apparatus for exhausting the products of combustion shown herein form the subject matter of a separate application, a sub-division of the present case, and I do not seek to cover herein features claimed in said concurrent application, but confine myself to my special means of effecting a circulation of water in and between the boiler and separator below the water level 110 common to both.

I am aware that it has been proposed to connect together independent tubular boilers in such manner as to afford a circulation of both water and steam between them, the products of combustion passing from the primary boiler 115 through the secondary boiler for the purpose of utilizing as far as possible the heat carried from a single furnace by the products of combustion; but in such case the steam is withdrawn directly from both boilers, and the secondary boiler is in no sense the equivalent of my steam separating chamber from which alone the steam is withdrawn. According to my invention the boiler is practically filled all the time with water and no steam whatsoever is separated and drawn off from the boiler shell, the whole gist of the invention consisting in the use of a separating chamber in 120 which the steam is separated from the water 125

115

110

115

120

125

130

at the water level above all connections with the boiler, the circulation being confined to the water and being entirely below the water line maintained in the separating chamber, 5 and the boiler being ordinarily below the said water line, and consequently full of water. The only exception to this might be that in the case of a vertical boiler a small space might be left in the boiler above the water 10 level common to both boiler shell and separating chamber, but in this case the boiler would be considered as practically full, since there would be no escape of steam collecting above the water line in the boiler, no circulation 15 of steam, and the circulation of water would be maintained entirely below the water line, the results being practically the same as in the arrangement of horizontal boiler and separating chamber herein shown and described.

What I claim as my invention, and desire to secure by Letters Patent, is—

1. The combination of a furnace, a boiler shell containing fire flues through which the 25 products of combustion from said furnace pass, an independent steam separating chamber situated in such relation to the said boiler shell that a water level and steam separating

surface common to both may be maintained in the separating chamber, a conduit situated 30 wholly below the water level and connecting the upper part of the said boiler shell with the separating chamber, and another conduit also situated entirely below the water level and connecting said separating chamber with the 35 lower portion of the said boiler shell, substantially in the manner and for the purpose described.

2. The combination of a furnace, a horizontal boiler shell formed with a series of fire 40 tubes an independent horizontal steam separating chamber above the boiler shell, a conduit connecting the upper portion of one end of the boiler shell with the separating chamber above, and a conduit connecting the other 45 end of said separating chamber with the lower portion of the steam boiler said last mentioned conduit consisting in part of an annular jacket surrounding the boiler shell, substantially in the manner and for the purpose 50 described.

CASSIUS C. PECK.
